[57] CLAIM

The ornamental design for a table or similar article, as shown and described.

DESCRIPTION

FIG. 1 is a perspective view of a table or similar article showing our design;

FIG. 2 is an elevation looking from one side of the table, the other side being identical;

FIG. 3 is an elevation looking from one end of the table, the other end being identical; and

FIG. 4 is a top plan view of the table.
